US0D1105964S

(12) **United States Design Patent** (10) **Patent No.:** **US D1,105,964 S**
(45) **Date of Patent:** **** Dec. 16, 2025**

(54) **PAIR OF EARRINGS**

(71) Applicant: **Harry Winston SA**, Plan-les-Ouates (CH)

(72) Inventor: **Delphine Abdourahim**, New York, NY (US)

(73) Assignee: **Harry Winston SA**, Plan-les-Ouates (CH)

(**) Term: **15 Years**

(21) Appl. No.: **29/961,877**

(22) Filed: **Sep. 9, 2024**

(30) **Foreign Application Priority Data**

Mar. 22, 2024 (WO) WIPO146224

(51) **LOC (15) Cl.** **11-01**

(52) **U.S. Cl.** **D11/42**
